UNITED STATES PATENT OFFICE.

WILFRED BRERETON CROFTON, OF YEOVILLE, JOHANNESBURG, SOUTH AFRICA.

INTERNAL-COMBUSTION ENGINE.

1,348,393.

Specification of Letters Patent. Patented Aug. 3, 1920.

Application filed May 22, 1918. Serial No. 236,017.

To all whom it may concern:

Be it known that I, WILFRED BRERETON CROFTON, a subject of the King of Great Britain, residing at 56 Harley street, Yeoville, 5 Johannesburg, Transvaal Province of the Union of South Africa, have invented certain new and useful Improvements in Internal-Combustion Engines, of which the following is a specification.

10 The present invention has reference to internal combustion engines, particularly four-stroke engines. The purpose of the invention is to provide novel means for increasing the amount of gas passed through 15 the engine, with the object of increasing the power of the engine without change of fuel, or of enabling low grade fuel, such as carbon monoxid, to be used, or of maintaining 20 the power of the engine in spite of lowered atmospheric pressure. The invention is here described as an attachment for existing engines of the motor car type.

In the accompanying drawings—

Figure I is a vertical section of the attachment and

Fig. II shows a four-cylinder four-stroke internal combustion engine fitted with the invention.

25 A', A², A³, A⁴ indicate the engine cylinders.

The induction valves 1 and exhaust valves 2 of said engine are left for operation in the usual manner; but it is necessary that the induction valves should not remain open 35 after the completion of the induction stroke of their respective pistons. 3 indicates the carbureter and 4 the induction manifold feeding the four cylinders.

5 is a compressor cylinder which is shown 40 as screwed in place of one of the valve caps. One such cylinder 5 is fitted to each engine cylinder. In the cylinder 5 is fitted the piston 6.

The lower end of the cylinder 5 is in direct communication with the engine cylinder so that the face 7 of the piston 6 is acted 45 upon by the explosion in the engine cylinder.

8 is a connection by which gas is conveyed 50 from the manifold 4 to each of the compressor cylinders 5. Its opening to each cylinder 5 is controlled by a separate non-return valve 9 opening toward the cylinder 5. The connection 8 is usually fitted with a throttle valve 10.

An outlet connection 11 joins each cylinder 5 to another engine cylinder; and it may be secured to the engine cylinder in place of the second valve cap. Said connection is fitted with non-return valve means to prevent flow of gas toward the compressor 60 cylinder. Since in the example shown the connections 11 are fairly long, non-return valves 12 and 13 respectively are fitted at each end of the connection.

The piston 6 is forced downward by a 65 spring 14 bearing against the cover 15 of the cylinder and steadied by a rod 16. Moreover when the piston is lifted a partial vacuum is created in the space 17 beneath the piston 6, which assists to return the 70 piston. A small flow of air is allowed to and from this space 17 by means of a cock 18. This provides sufficient air to form a cushion to deaden the shock of stopping the return of the piston 6 and also prevents accumulation of air which would destroy the 75 vacuum. The degree of the latter and consequently the resistance of the upward stroke of the piston may be varied by opening or closing the cocks 18, by means of a 80 common rod 19.

The delivery connection 11 from each cylinder 5 is taken to the next firing cylinder of the engine. That is to say, in the example shown, the compressor cylinder 5 of engine 85 cylinder A' delivers to engine cylinder A², that of cylinder A² to A⁴, that of cylinder A⁴ to A³ and that of cylinder A³ to cylinder A'.

The operation is as follows:

At each explosion in an engine cylinder, the corresponding piston 6 is forced upward, and—upon the subsequent fall of pressure in the engine cylinder—is forced downward again. In so moving down it draws 95 into its cylinder 5 a charge of gas from the induction pipe 4 and connection 8. At the next explosion in its engine cylinder, this charge is ejected from the cylinder 5 into the next firing cylinder, say A². This cylinder 100 A² has already made its induction stroke and drawn in, directly from the induction pipe 4, a charge of gas at rather below atmospheric pressure; and its induction valve 1 has closed.

The additional charge from the compressor cylinder 5 is thus added to the ordinary induced charge. The augmented charge is

thereupon compressed by the upstroke of the piston 20 in cylinder A² and is fired and exhausted in the usual way.

- The result is that the pressure at the commencement and termination of the working stroke of the engine is raised and the power of the engine is increased. In the case of a car engine which is not ordinarily required to develop its full power and using petrol, 5 of which economy is a desideratum, the compressors would be cut out of action during the ordinary running of the engine. This may be accomplished by so adjusting the resistance of the springs 14 and the vacuum in the space 17 that the piston 6 would not be lifted by the pressure developed by the explosion in the engine cylinder. Upon the engine throttle being further opened, without substantial increase of engine speed, the piston 6 10 becomes operative and the power of the engine is immediately increased considerably, since the injection of the increased charge increases the pressure of the explosion and so reacts further to increase the injection up to the limit which the apparatus is capable 15 of. When however the engine is running at high speed, the engine piston 20 offers less resistance to the explosion and there is a consequent tendency for the compressors to become inoperative. The control of the operation of the compressors may however be effected manually by closing the throttle 10 to render them inoperative and opening said throttle to render them operative. 20
- On the other hand, when using cheap low grade fuel, economy of which is not important, or which does not produce high explosive pressure, but which requires high compression for ignition, the compressor pistons are arranged to operate the whole time. 30
- Again in the case of an aeronautical engine it is desirable to be able to maintain the volumetric efficiency of the engine cylinder in spite of decreased density of the atmosphere at a height. With this object the 35

compressor cylinders may be cut out at the beginning of a flight by the throttle 10 and brought into operation by gradually opening said throttle as greater altitudes are reached. 50

Having now particularly described and ascertained the nature of my said invention and in what manner the same is to be performed I declare that what I claim is:—

1. In combination with a multi-cylinder 55 four-stroke internal combustion engine, a compressor device having a piston exposed to the explosion in an engine cylinder and thereby driven on its working stroke, said compressor drawing gas from a suitable 60 source such as the engine inlet manifold, and delivering its charge to another engine cylinder to be compressed for ignition therein.

2. Apparatus as claimed in claim 1 in 65 which the connection is such that the compressor charge is admitted to the engine cylinder after the induction stroke in the latter.

3. Apparatus as claimed in claim 1, in 70 which the compressor cylinder is fitted with a single piston one end of which is exposed to the explosion and the other end of which operates as a compressor piston.

4. A compressor attachment for an internal combustion engine, comprising a cylinder, a piston therein having one face adapted to be acted upon by explosion in the engine and the other face serving as a compressor piston, means tending to force the piston toward one end of the cylinder, means to attach the explosion end of the cylinder to an engine cylinder, means to connect the other end of the cylinder to another engine cylinder and to a source of fuel gas, and valves directing the flow of gas from the source 80 to the compressor cylinder and thence to the engine cylinder. 75

In testimony whereof I affix my signature.

WILFRED BRERETON CROFTON.
